(57) **ABSTRACT**

A new *Pelargonium* plant named 'Amri Pur,' particularly distinguished by the brilliant red-purple semi-double flowers, medium sized, round inflorescences well above the foliage, medium green foliage with strong zonation, and well-branched, rounded, medium to tall plant habit.

1 Drawing Sheet

1

Latin name of the genus and species of the plant claimed:
Pelargonium×hortorum.
varietal denomination: 'Amri Pur'.

BACKGROUND OF THE NEW PLANT

The present invention comprises a new zonal *Geranium*, botanically known as *Pelargonium×hortorum* and hereinafter referred to by the variety name 'Amri Pur.'

'Amri Pur' is a product of a planned breeding program. The new cultivar 'Amri Pur' has deep red-purple flowers with weak scarlet eyes, medium green foliage with strong zonation, and medium to tall, rounded plant habit.

'Amri Pur' originated from a hybridization made in the October 2004 in a controlled breeding program in Gilroy, Calif., U.S.A. The female parent was the unpatented seedling designated '10153-1,' with rose-red flower color. '10153-1' has more petals per flower and less tight plant habit than 'Amri Pur.'

The male parent of 'Amri Pur' was an unpatented hybrid seedling identified as '9843-2' with orchid flower color. '9843-2' has a less vigorous growth habit than 'Amri Pur.'

The resulting seeds were sown in March 2005. 'Amri Pur' was selected as one flowering plant within the progeny of the stated cross in May 2005 in a controlled environment in Gilroy, Calif.

The first act of asexual reproduction of 'Amri Pur' was accomplished when vegetative cuttings were propagated from the initial selection in the summer of 2005 in a controlled environment in Gilroy, Calif.

Horticultural examination of plants grown from cuttings of the plant initiated in the early spring of 2006 in Gilroy, Calif., and continuing thereafter, has demonstrated that the combination of characteristics as herein disclosed for 'Amri Pur' are firmly fixed and are retained through successive generations of asexual reproduction.

'Amri Pur' has not been observed under all possible environmental conditions. The phenotype may vary significantly with variations in environment such as temperature, light intensity and day length.

Plant Breeders' Rights for this cultivar was applied for in Canada on Dec. 24, 2007 and in Germany on Jun. 30, 2008.

2

'Amri Pur' has not been made publicly available more than one year prior to the filing of this application.

DESCRIPTION OF THE DRAWINGS

5 The accompanying photographic drawing shows typical flower and foliage characteristics of 'Amri Pur' with colors being as true as possible with an illustration of this type.

The photographic drawing shows a flowering potted plant 10 of the new variety in a 6 inch pot and a close-up of the flowers.

Both of the photographs were taken in November 2007 in Gilroy, Calif. Both were grown in Gilroy, Calif. and were approximately two months old.

DETAILED BOTANICAL DESCRIPTION

15 The measurements were taken in Hillscheid, Germany, on Aug. 28, 2008 on about 6 month old plants that were growing outdoors in the trial field. Culture of these plants had started in early March when rooted young plants were planted into 12 cm pots and were grown out, unpinched, on benches in a greenhouse. In mid May they were transplanted, 3 each, into 42 cm tubs which were placed outdoors.

20 Color chart used: The Royal Horticultural Society Colour Chart (R.H.S.), 2001.

BRIEF SUMMARY OF INVENTION

25 The following observations, measurements, and comparisons 30 describe plants grown indoors and outside in Hillscheid, Germany, and in Chatellerault, France. The following traits have been repeatedly observed and are determined to be basic characteristics of the new variety. The combination of these characteristics distinguishes this *Pelargonium* (common name zonal *Geranium*) as a new and distinct variety.

1. Brilliant red-purple flowers, upper petals with weak scarlet 'eyes'
2. Semi double flower type, and medium to large, round inflorescences
3. Medium green foliage with relatively strong zonation
4. Medium to strong vigor, and well branched
5. Mounding habit (relatively high, but not very wide) with the flower heads well above the foliage

<i>Width.</i> —0.9–1.1 cm.	10	<i>Stigma color.</i> —RHS 53B.
<i>Shape.</i> —Elliptical.		<i>Number of stamens.</i> —5–7.
<i>Calyx:</i>		<i>Length of anthers.</i> —2–3 mm.
<i>Number of sepals.</i> —5.		<i>Anther color.</i> —RHS 47A.
<i>Color of sepals.</i> —Mainly green, RHS 143A to 143B, a little anthocyanin RHS 181A at base.		<i>Length filaments.</i> —6–7 mm.
<i>Length of sepals.</i> —0.9–1.1 cm.		<i>Color of filaments.</i> —Nearly white, RHS 69D, at base; upper part pink, RHS 68A.
<i>Width of sepals.</i> —4 mm (largest sepal), 2–3 mm for the other ones.		<i>Pollen amount.</i> —Moderate (usual amount for the species).
<i>Sepal shape.</i> —Lanceolate.		<i>Color of pollen.</i> —RHS 28A, yellow orange.
<i>Apex shape.</i> —Acute.		<i>Fertility/seed set.</i> —No seed set observed.
<i>Margins.</i> —Entire.		<i>Disease/pest resistance:</i> Has not been observed on this hybrid.
<i>Texture.</i> —Glandular hairs, long soft hairs.		What is claimed is:
<i>Reproductive organs:</i>		1. A new and distinct variety of <i>Pelargonium</i> plant named 'Amri Pur,' substantially as illustrated and described herein.
<i>Pistil.</i> —1.		
<i>Length.</i> —7–8 mm.		
<i>Style color.</i> —RHS 53A, purple-red.		
<i>Style length.</i> —3 mm.
